UNIVERSAL LINK

Filed March 18, 1950

Fig. 1

Fig. 2

Technical drawings of a cylindrical component. Fig. 1 shows a side view with internal features and dimensions labeled 1/4, 15, and 19. Fig. 2 shows a top-down view of the internal components.

Technical drawings of three cylindrical components labeled Fig. 5, Fig. 6, and Fig. 7.

Fig. 5 shows a cylinder with a total height of 20. The top part has a height of 6, a diameter of 23, and a shoulder of 27. The bottom part has a diameter of 27 and a shoulder of 20.

Fig. 6 shows a cylinder with a total height of 20. The top part has a diameter of 23 and a shoulder of 27. The bottom part has a diameter of 25 and a shoulder of 27.

Fig. 7 shows a cylinder with a total height of 20. The top part has a diameter of 26 and a shoulder of 23. The bottom part has a diameter of 25 and a shoulder of 26.

Fig. 3

Diagram of a rectangular frame with rounded corners and a central slot. The frame is labeled with the number 13 at the bottom left and 11 at the top left. The central slot is labeled with the number 12 at the top center.

UNIVERSAL LINK

Charles W. Kampfer, St. Paul, Minn.

Application March 18, 1950, Serial No. 150,367

6 Claims. (Cl. 74—246)

1

My invention relates to an improvement in universal link wherein it is desired to provide a conventional chain so constructed that it may turn in any desired direction.

In the use of conveyors designed for conveying milk bottles and the like, it is desirable that the links of the chain be so constructed as to permit the chain to change direction from time to time. The chain usually is of the endless type and is actuated by sprockets over which the chain extends. It is desirable that the chain not only be able to extend around these sprockets, but it is also desirable that the chain may be flexible in other directions. The present invention relates to an improved universal link of this type. In my previous Patent No. 1,893,141, issued January 3, 1933, I disclosed a link of somewhat similar form to that of the present invention. The links included U-shaped bodies which were slotted horizontally and vertically in such a manner that the horizontal slots extended into the links from one end thereof and the vertical slots extended into the links from the opposite end thereof. The links were connected by connecting pivots having a vertical pivot at one end and a horizontal pivot at its other end. The present invention shows an improved manner of constructing these universal links and an improved manner in manufacturing the connecting pivots so that the links may be more easily detached when desired.

A feature of the present invention lies in the provision of a conventional chain composed of universal links having platform pieces connected to one side of each link. These platform pieces form a support for the bottles or other articles conveyed by the chain.

A feature of the present invention lies in the provision of a conveyor chain having platform pieces secured to the upper surface of each link, the platform pieces interfitting to provide a substantially continuous support.

A further feature of the present invention lies in the provision of a conveyor chain connected by connecting pivot members having right angularly arranged pivots, one of which is removable.

An added feature of the invention lies in the specific manner in which the links are designed so as to be removable without the use of tools.

These and other objects and novel features of my invention will be more clearly and fully set forth in the following specification and claims.

In the drawings forming a part of my specification:

2

Figure 1 is a plan view of a section of chain showing the construction thereof.

Figure 2 is a side elevation view of a series of links forming the conveyor chain.

5 Figure 3 is a vertical section centrally and longitudinally through a pair of connected conveyor chain links.

Figure 4 is a diagrammatic view of the blank of which one of the links is partially formed.

10 Figure 5 is an elevation view of a portion of one of the connecting pivot members for connecting adjacent links.

Figure 6 is a top plan view of the device illustrated in Figure 5.

15 Figure 7 is a plan view of a pivot used in conjunction with the pivot members illustrated in Figures 5 and 6.

Figure 8 is an elevation view of the pivot member shown in Figure 7.

20 Figure 9 is an end view of the pivot shown in Figures 7 and 8.

The conveyor chain illustrated in the drawings is composed of a series of links A, each of which is identical in form. Each link is preferably formed of an elongated strip 10 of stainless steel or other suitable material. Each strip 10 is preferably formed as illustrated in Figure 4 of the drawings and includes an elongated slot 11 midway between the ends thereof and a relatively shorter slot 12 near each end of the strip. The slots 11 and 12 are aligned. One edge of the strip 10 projects above the level of the remainder of the strip as indicated at 13 so as to form a support for the platform piece which will be later described in detail.

35 35 The strip 10 illustrated in Figure 4 of the drawings is bent into U-shaped form, the bend being located at the center part of the link so that entire bent end of the link is slotted by the slot 11. The two slots 12 are parallel and in opposed relationship, the ends of the strip being parallel on either side of the center bend.

A platform piece 14 is brazed, welded, or otherwise secured to the upper surface of the bent strip 10 to form a support for articles being conveyed. As indicated in Figure 1 each platform strip 14 is rounded at one end as indicated at 15 and is notched at its other end along a similar curve as indicated at 16 so as to accommodate the rounded forward end of the next adjacent link. The platform pieces 14 are spaced slightly apart to permit the conveyor chain to bend slightly in an upward direction and to provide clearance between adjacent links. It will be noted, however, that the rounded forward end

15 of one link extends beyond portions of the notched opposite end 16 of the next adjacent link so that portions of the two platform pieces overlap.

It will also be noted from Figure 1 of the drawings that the rounded forward end of each platform piece 14 has as its center of curvature, the center of the bent end of the link strip 10. When the individual links bend laterally about a vertical pivot, the center of pivotal motion coincides with the center of curvature of the bent or folded end of the link strip 10. The platform plates 14 are curved along a similar center so as to remain in proper relationship regardless of the angularity therebetween.

The connecting elements connecting the various links are best illustrated in detail in Figures 5 through 9 of the drawings. Each connecting member includes a vertical pivot 17 which is rounded along its inner surface as indicated at 19 on a radius of curvature slightly less than the radius of curvature of the bent strip 10. Thus the rounded vertical surface 19 bears against the inner surface of the rounded end of the link strip 10 in folded condition of this strip. When one of the links A pivots relative to the other link along a vertical axis, the rounded surface 19 of the connecting member slides over the rounded inner surface of the bent end of the link.

The vertical pivot 17 is connected along a longitudinally extending connecting portion 20 to a ring or bearing 21. This ring or bearing 21 is provided with an elongated aperture 22 therethrough. The aperture 22 is somewhat oval in shape and its vertical dimension is greater than its longitudinal dimension.

A transverse pivot 23 which is used in conjunction with the connecting member 24 just described, is best shown in Figures 7 through 9 of the drawings. This pivot 23 includes a center portion 25 and opposite end portions 26. The end portions 26 are cylindrical in form and serve as pivots about which the links may pivot. The central portion 25 is oval in cross section to fit the slot 22 in the connecting member end 21. As illustrated in Figures 8 and 9 of the drawings, the oval or elongated shape of the center portion 25 provides shoulders 27 at either end of the center portion 25 for a purpose which will now be described.

It will be noted that the slot 22 of the connecting member is elongated in a vertical direction. The slots 12 of the link strips 10 are of a height slightly greater than the diameter of the cylindrical ends 26 of the pivot 23. In other words, the pivot ends 23 fit snugly in the slots 12 without excessive play. The slots 12 are not of sufficient height, however, to accommodate the oval center portion 25 of the pivot. Thus when the pivots 23 are in place, the shoulders 27 on either end of the center portion 25 abut against the inner surfaces of the link sides above and below the slots 12 and are held in place thereby.

Obviously the center portions 25 of the links 23 need not be oval in cross section. These portions of the link do not pivot relative to the ring shaped member 21 in which they are engaged so that the center portions 25 could be rectangular in cross section or some other such shape as long as the structure provided shoulders, such as 27 above and below the cylindrical pivot end portions 26 so as to prevent or limit longitudinal sliding of the pivots when engaged.

In assembling the links of the conveyor chain, the connecting members 24 are turned at right

angles to their normal position illustrated in Figures 2 and 3 of the drawings so that the oval center portion 25 of the pivot extends longitudinally of the slot 12. The connecting portion 24 5 illustrated in Figures 5 and 6 of the drawings is held between the spaced ends of the link strip 10 so that the oval aperture 22 is in registry with the slots 12. While in this position the pivots 23 10 may be inserted through the slots 12 and through the aperture 22. The center portion 25 being 15 enclosed within the aperture 22. When the connecting member 24 is swung into longitudinal position as shown in Figures 2 and 3, the center portion 25 of the pivot is pivoted out of registry with the slots 12 so that the shoulders 27 abut against the link strips upon axial movement of the pivot 23 relative to the links.

Thus it will be seen that the links may be connected or disconnected when arranged at right angles to one another. The vertical pivot 17 is 20 first engaged in the rounded end of the link strip 10 by turning the connecting member at right angles so that the axis of the pivot 17 extends longitudinally of the slot 11. The pivot end 17 of the connecting member is inserted through one side of the slot 11 until the pivot 17 is within the link between the parallel sides thereof. The connecting member is next turned at right angles so as to engage in the rounded end of the link strip as illustrated. After the pivot end 17 of each connecting member has been connected to its link, the end 21 is placed in registry with the slots 12 and the pivot 23 inserted in the manner previously described.

In accordance with the patent statutes, I have 35 described the principles of construction and operation of my universal link construction, and while I have endeavored to set forth the best embodiment thereof, I desire to have it understood 40 that obvious changes may be made within the scope of the following claims without departing from the spirit of my invention.

I claim:

1. A conveyor chain including a series of connected links, each link including a strip of U-shaped form, a slot extending into said strip intermediate the edges thereof, said slot extending through the rounded end of the U toward the other free ends thereof, a connecting member including a pivot engaging the rounded end of the link on opposite sides of the slot, a connecting portion extending through the slot, and a bearing on said connecting portion having an aperture of elongated section, a second pivot having a center portion removably supported by said bearing and arranged on an axis at right angles to the axis of the first named pivot, said second pivot being provided with shoulders at either end thereof engageable against the sides of the link.

2. A conveyor chain including a series of links including a U-shaped body having a rounded end and parallel sides, a slot extending through said rounded end and said parallel sides and extending toward the opposite end of the body, a connecting member engaged in the rounded end of the link body, the connecting member including a pivot engageable against the rounded end of the body on opposite sides of the slot, a connecting portion extending through the slot, and a bearing supported by said connecting portion, said bearing supporting a second pivot arranged on an axis at right angles to the axis of the first named pivot, said second pivot having a center portion projecting beyond the cross sectional dimensions of the ends thereof to form shoulders

between the center portion and the end portions of the second pivot, said shoulders being engageable against the parallel portions of the U-shaped link body of the next adjacent link.

3. The structure described in claim 2 in which the center portion of the second pivot is of oval cross section and the ends of the pivot are of cylindrical cross section.

4. The structure described in claim 2 in which the center portion of the second pivot is generally oval in cross section.

5. A universal link for a conveyor chain including a U-shaped body having a rounded end and parallel side arms, a slot extending into said link, said slot extending through the rounded end and into the parallel side arms, a pair of slots through said side arms in aligned relation near the free ends thereof, a connecting member including a pivot engaging the rounded end of the link body on opposite sides of said first named slot, a connecting portion extending through said first named slot, and a bearing portion supported by said connecting portion, a second pivot including a center portion and opposite end portions, the center portion extending beyond the dimensions of the end portions to form shoulders between the center portion and the end portions, the center portion being removably supported by said bearing portion and said end portions being designed for engagement in the pair of oppositely aligned slots of a second link.

6. A connecting block for a universal link pro-

vided with spaced side walls having transversely aligned slots therein, the block comprising oppositely directed trunnions, a perpendicularly extending shank, a bearing ring connected to the shank, said ring having an oval aperture whose axis is perpendicular to the axis of said trunnions and said shank, and a pivot pin including a central portion having dimensions complementary with said oval aperture and receivable thereby and oppositely directed trunnions carried by said central portion, said last named trunnions and the minor dimension of said central portion being of a size sufficiently small to be received by the slots of said link and the major dimension of said central portion being of a size too great to be received by said slots.
